In France August 25, 1950

Term of patent 7 years

(Cl. D52—1)

To all whom it may concern:

Be it known that I, Elie Paul Emile Deschamps, a citizen of France, residing at Oyonnax, France, have invented a new, original, and ornamental Design for Fertility Slide Rule, of which the following is a specification, reference being had to the accompanying drawing, forming part thereof.

The drawing figure is a perspective view of a fertility slide rule, showing my new design. The rear of the device is plain.

I claim:

The ornamental design for a fertility slide rule, as shown and described.

ELIE PAUL EMILE DESCHAMPS.
